United States Patent Office

Des. 203,037

Patented Nov. 30, 1965

203,037

POST

Louis Blum, 2312 Tilbury St., and William J. Horgan, Jr.,
1299 Folkstone Drive, both of Pittsburgh, Pa.

Filed Dec. 13, 1963, Ser. No. 77,786

Term of patent 14 years

(Cl. D13—7)

FIG. 1.

FIG. 2.

FIG. 3.

FIG. 1 is a perspective view of a post embodying our new design;

FIG. 2 is another perspective view thereof, the stair tread, railing and connecting brackets being shown for illustrative purposes only; and,

FIG. 3 is a fragmentary perspective view of a modified form of the base portion of the post the remaining top portion thereof being identical with the top portion of the post shown in FIG. 1.

We claim:

The ornamental design for a post, as shown and described.
